J. R. ASH

INTERNAL COMBUSTION ENGINE ATTACHMENT

Filed April 3, 1923

FIG. 1.

FIG. 2.

FIG. 3.

Fig. 4.

Inventor
J.R. Ash
By William J. Jacobi
Ottawa

UNITED STATES PATENT OFFICE.

JAMES R. ASH, OF GUYS MILLS, PENNSYLVANIA.

INTERNAL-COMBUSTION-ENGINE ATTACHMENT.

Application filed April 3, 1923. Serial No. 629,629.

To all whom it may concern:

Be it known that I, JAMES R. ASH, a citizen of the United States, residing at Guys Mills, in the county of Crawford and State 5 of Pennsylvania, have invented certain new and useful Improvements in Internal-Combustion-Engine Attachments, of which the following is a specification.

The invention contemplates a chamber 10 having communication with the internal combustion engine cooling system and the intake manifold of the engine whereby to conduct vapor or steam from the cooling system into the engine cylinders thereby eliminating carbon deposits from the cylinders.

Still another object of the invention is to provide a device of this character having a sediment trap to catch any sediment from the internal combustion engine cooling system 20 and retain the same against being drawn into the engine cylinders.

Another object of my invention is to provide a device of this type that can be associated with any type of internal combustion engine now in use and can be installed thereon by the average person and when in use will reduce the consumption of fuel to a minimum and increase the power of the engine to a maximum degree.

With the preceding and other objects and advantages in mind, the invention consists in the novel combination of elements, constructions and arrangements of parts and operations to be hereinafter specifically referred to, claimed and illustrated in the accompanying drawings wherein—

Figure 1 is a side elevation of my attachment associated with an internal combustion engine.

Figure 2 is a vertical sectional view of the same taken on line 2—2 of Fig. 1.

Figure 3 is a horizontal sectional view taken on line 3—3 of Fig. 2 showing the L-shaped pipe in elevation.

Figure 4 is a detail view showing the T-shaped head of the inlet pipe in top plan.

Referring in detail to the drawing wherein corresponding characters of reference denote corresponding parts throughout the several views, the numeral 5 denotes a conventional internal combustion engine having the usual intake manifold 6 and a carburetor 7.

My invention comprises a cylindrical receptacle 8 having a conical bottom 9 formed with a threaded nipple 10 having threaded

engagement with a transparent receptacle or sediment trap 11 which may be removed at various times to empty the contents therein.

The receptacle 8 is supported upon the engine 5 and held in proper position by means of suitable brace rods 12 which are conveniently secured to the engine block and support a ring 13 which is adapted to encircle the receptacle 8 and snugly hold the same adjacent the exhaust manifold 14.

Extending through one side of the receptacle 8 is an L-shaped pipe 15 having its vertical leg arranged in the center of the receptacle 8 and supported therein by a suitable brace 16 carried by the inner wall of the receptacle 8 and directly above and in close proximity to the upper end of the trap 11. The horizontal arm of this pipe terminates in a substantially T-shaped head 17 forming an air inlet disposed in close proximity to the exhaust manifold 14 of the internal combustion engine by means of a supporting plate 17' and adapted to conduct heated gases or air from the atmosphere into the receptacle 8. Leading from the internal combustion engine cooling system and preferably the radiator at a point where the upper end of the overflow pipe 18 is usually arranged and having its other end extended through the receptacle 8 and disposed within the collar 10 to conduct water into the trap 11. The water contained in the trap 11 is vaporized by the hot air from the pipe 15.

The top of the receptacle 8 is provided with a conical top or cover 19 which is provided with a centrally disposed elbow 20 for communication with the receptacle 8 for the purpose hereinafter to be more fully described. The free end of the elbow 20 is fitted to one end of a flexible hose or tube 21 which is connected at its opposite end to the carburetor 7.

It will be thus obvious that the operation of the engine will create a vacuum in the cylinder 8 which in turn draws the vapor and heated air into this pipe 21 and thence into the carburetor 7 and finally into the intake manifold 6 of the internal combustion engine 5.

With my device it will be seen that the air drawn through the inlet 17 and the pipe 15 into the receptacle 8 will be vaporized and conducted into the intake manifold of the engine. Also any sediment that may

be contained in the water carried from the radiator by the pipe 18 will be deposited in this trap 11 and settle in the bottom thereof.

5 A pet cock 22 may be provided in the bottom of the carburetor 7 for the purpose of draining the same whenever necessary to remove any foreign matter which has collected therein.

10 From the foregoing description of the construction of my improved apparatus, it will be seen that I have provided a simple, inexpensive and efficient means for carrying out the objects of the invention and 15 while I have particularly described the elements best adapted to perform the functions set forth, it is obvious that various changes in form, proportion and in the minor details of construction may be resort 20 ed to, without departing from the spirit or sacrificing any of the principles of the invention.

What I claim as new and desire to secure by Letters Patent is:—

25 1. An attachment for internal combustion engines comprising a receptacle provided with a threaded collar at its lower end, a jar adapted to contain water and having its neck threadedly engaged with the 30 collar, a conduit leading into the receptacle

and adapted to have one end arranged in close proximity to the exhaust manifold of an internal combustion engine whereby to conduct hot air into the receptacle and vaporize water contained in the jar, and 35 an outlet leading from the receptacle and adapted to be arranged in communication with a carburetor to supply vaporized products thereto.

2. The combination with an internal combustion engine; of a receptacle, brackets securing the receptacle to the internal combustion engine, the receptacle being provided with a frusto-conical bottom which terminates in a threaded collar, a jar having its neck threaded into the collar, an L-shaped pipe arranged within the receptacle and having its vertical leg arranged concentric to the neck of the jar and having its horizontal leg terminating at a point 40 adjacent the exhaust manifold of the engine whereby to conduct hot air from this point and discharge the same into the receptacle, and a tube leading from the upper end of the receptacle and having communication with the carburetor to conduct vaporized products into the latter. 45

In testimony whereof I affix my signature.

JAMES R. ASH.
